UNITED STATES PATENT OFFICE.

JULIUS B. WANTZ, OF OAK PARK, ILLINOIS, ASSIGNOR TO VICTOR X-RAY CORPORATION, OF CHICAGO, ILLINOIS, A CORPORATION OF NEW YORK.

WATER-COOLED ULTRA-VIOLET APPARATUS.

Application filed October 22, 1924. Serial No. 745,263.

To all whom it may concern:

Be it known that I, JULIUS B. WANTZ, a citizen of the United States, residing at 324 North Harvey Avenue, Oak Park, in the 5 county of Cook and State of Illinois, have invented new and useful Improvements in Water-Cooled Ultra-Violet Apparatus, of which the following is a specification.

The present invention relates to an apparatus 10 employed for the production of ultra-violet rays and has particularly to do with a cooling system employed in conjunction with the lamp from which the ultra-violet emanations proceed.

15 Among the objects of the invention are the provision of means for adequately cooling a lamp intended for the purpose indicated, means for cooling a liquid medium and circulating it about such lamp, the combination of air and water cooling means in 20 a single apparatus, and the adaptation of safety means for protecting the apparatus against the possibility of incorrect connections with respect to the electric circuits 25 therein.

Further object of the invention is to provide visual signal means for determining the adequacy of the flow of such cooling medium and an additional object of the invention is to provide, in association with an 30 ultra-violet apparatus a cooling device of unique and improved design which will positively protect the lamp from overheating and at all times disclose to the operator the 35 precise condition of the cooling fluid within such cooling system.

These, and such other objects as may hereinafter appear, are obtained by the combination, construction, and arrangement of the 40 several elements which constitute the cooling system hereinafter to be described, which system is fully illustrated in the two sheets of drawing accompanying this specification and hereby made a part thereof.

45 Figure 1 is an elevation of an ultra-violet ray apparatus contained in a cabinet, the lamp being disassociated therefrom and the front of the cabinet removed;

Figure 2 is a plan view of the circulatory 50 and cooling elements as disposed in said cabinet; and

Figure 3 is a diagrammatic illustration of the wiring system employed.

Like reference characters are used to 55 designate similar parts in the description which

follows and in the several figures of the drawings.

The ordinal 10 is used to designate an upright cabinet for containing the apparatus except the lamp and from which the cover 60 (not shown) is removed. Such cabinet may be provided with casters 11 for the purpose of ready transportation about the laboratory or office where the apparatus is employed. As the invention resides in the cooling and 65 wiring systems and the combination thereof, the various other parts of the apparatus will only be generally described. Those parts of the apparatus which are disclosed in Figure 1 comprise a tungar transformer designated 70 12, tungar rectifying bulbs designated 13, a tungar reactance or choke coil identified by the numeral 14, ballast resistance identified by the numeral 15, a meter disposed upon the exterior of the cabinet and designated 16, and control or operating handles 75 17 and 18 disposed upon the opposite sides of the top of said cabinet adjacent meter 16.

Without the cabinet 10 is disposed a water jacketed hood 19 within which is a 80 lamp (not shown) for supplying ultra-violet emanations. Such hood 19 is provided with an inlet pipe 20 and an outlet pipe 21, both pipes being flexible and joined to the water jacketed lamp casing 19 by suitable water 85 tight connections as disclosed in Figure 1.

The system for circulating a cooling medium through the jacketed casing 19 comprises a pump 22 of the rotary type driven by motor 23 flexibly connected to said pump 90 at 24. Said pump 22 and motor 23 are mounted upon a platform 25 having a plurality of legs 26 for securing it to the bottom of cabinet 10 while elevating said motor sufficiently to allow for unhampered rotation of fan 27 which is secured to motor 23 at the end of the shaft opposite flexible connection 24.

The main supply of water is contained in a reservoir 28 having depending section 29 100 comprising a radiator through which the water or other cooling liquid trickles or flows, the air current generated by fan 27 being driven through such portion 29 for the purpose of cooling the circulating 105 medium.

Intermediate reservoir 28 and pump 22 is disposed a pipe 30 which is joined to the base of radiator section 29. From the rotary pump 22 the water drawn from reservoir 28 110

through pipe 30 is forced to the jacketed casing 19 through the inlet pipe 20.

Such water as has been forced into jacketed casing 19 by rotary pump 22 is discharged from said casing through pipe 21 into a member comprising a basin or bowl 31, preferably of metal. Said bowl 31 has a funnel shaped bottom orificed at 32 to permit of the flow therefrom of any liquid which may gather in said bowl 31. A discharge pipe 33 is connected to orifice 32 and discharges fluid from bowl 31 into reservoir 28. Preferably the discharge pipe 33 is connected to a cap 28^a for the opening in reservoir 28 to allow it to be filled and refilled. The bowl 31 terminates in a flanged top abutting the top of cabinet 10, such flanged portion determining the position of bowl 31 with respect to the top of said cabinet.

Pipe 21 is directly connected to an elbowed member 35 comprising an horizontal section substantially in alignment with pipe 21 and a vertical section connected to said horizontal section and terminating in a vent or opening 36 at the topmost portion thereof. A transparent glass cylinder or bell 37 having a closed end 38 is made to fit snugly into the cylindrical portion of vessel 31. The open portion of such glass cylinder 37 rests upon the bottom of said metallic vessel 31 while the closed end 38 of said glass cylinder 31 completely surrounds the orifice or vent 36 in elbowed member 35. Water is forced from the jacketed casing 19 through the pipe 21 into the elbowed member 35 completely enclosed within vessel 31 and its glass covering 37. The force with which cooling water is discharged from pipe 21 into elbowed member 35 forces a jet to play upon the end 38 of glass cover 37. After striking cover 37 the water is scattered about and its force is lost permitting it to fall into funnel shaped vessel 31 to be carried by pipe 33 to reservoir 28.

The circulation of cooling medium, hence, is from the pump 22 through conduit 20 to jacketed casing 19 where the cooling effect upon the lamp is produced; from jacketed member 19 through conduit 31 an elbowed member 35 from which it is discharged through the vent 36 against the closed end 38 of the glass cylinder 37; through the base of member 31, orifice 32, pipe 33 to reservoir 28; through the lower section 29 of said reservoir, into pipe 30 and back to pump 22 to again be circulated through the system.

The operator of the apparatus may always determine the flow of the cooling medium by visualizing the jet of water forced out of vent 36. If the water in the system becomes too hot, excessive vapor or condensation will display itself in glass cylinder 37. Should the flow of water become

reduced or cease through obstruction or lack of water in the circulatory system, such fact will be instantly communicated to the operator through his sense of sight.

It is sometimes desirable to employ in a single apparatus lamps requiring different voltage as, for example, a fifty volt lamp, and a seventy to ninety volt lamp. In the device here illustrated, the fifty volt lamp is water cooled but the seventy to ninety volt lamp is air cooled. Sufficient voltages change the character of the emanations from the lamps, and a lamp of lower voltage has the greater tissue destroying effect.

Reference should now be had to Figure 3 in order to understand the wiring system of the device. In view of the different voltages required because of the use of lamps of different capacities, and because it is desirable to water cool the fifty volt lamp and air cool the other, it is necessary to design a wiring system which will cause the circulatory system to act only when the fifty volt lamp is used, and which shall cut out the motor driving the pump and fan when the seventy to ninety volt lamp is employed. Incidentally it is necessary to prevent a lamp of low voltage from being charged with current from a circuit of higher voltage.

Numerals 50 and 51 indicate mains leading into the tapped primary winding of a transformer 52, designated 12 in Figure 1. A line switch 53 may be arranged upon said mains 50 and 51.

The diagram indicates that the rectifying bulbs 56, designated 13 in Figure 1, have independent secondaries, but these rectifying bulbs could be directly connected by tapping the secondary of transformer 52. Said rectifying bulbs 56 convert the alternating current induced in the tapped secondary winding of transformer 52 into unidirectional pulsating current, which current is conveyed, in a manner now to be described, to the lamp through mains 54 and 55 connected to the terminals of said secondary winding of transformer 52.

The water cooled lamp is designated by the numeral 57. The circuit for said lamp 57 comprises the main 55 from one terminal of transformer 52, a reactance coil 58 designated 14 in Figure 1, a resistance 59 designated 15 in Figure 1, a main 60, water cooled lamp 57, a main 61, to a selector switch 62, and from said switch 62 through main 54 back to the other terminal of the secondary of transformer 52. With the closing of the switch 62 for the purpose of connecting mains 61 and 54, a second closed circuit is established which circuit serves the motor 23 driving pump 22 and fan 27 referred to above. Said motor 23 is fed by a circuit comprising a main 63 from one terminal of the secondary of transformer 52 to motor 23,

to a main 64, to switch 62, and by way of main 54 to the other terminal of the secondary of transformer 52.

In the connections referred to, the circuits 5 relating to the seventy to ninety volt air cooled lamp are open. It is impossible to close the water cooled lamp circuit without concurrently closing the motor circuit just described. It is, therefore, impossible to operate the water cooled lamp without establishing connections for the cooling system therefor.

In using the air cooled lamp, designated 65, the circuits are as follows. In the case 15 of a seventy volt current, the circuit is established through main 55, connected to one terminal of the secondary of transformer 52, reactance coil 58, resistance 59, a main 66 to lamp 65, main 67 to selector switch 62, 20 and main 54 to the other terminal of the secondary of transformer 52.

In the ninety volt circuit, the connections are through said main 55 from one terminal 25 of the secondary of transformer 52, reactance coil 58, a main 68, selector switch 62, a main 69 to resistance 59, main 66 to lamp 65, main 67 to selector switch 62, and main 54 to the other terminal of the secondary of transformer 52.

30 In this manner the resistance 59 is adapted to control the current required by its adjustability. In the case of the water cooled lamp, a pressure of fifty volts is obtainable, while in the case of the air cooled lamp, resistance is reduced so that a voltage of 35 seventy volts may flow, and in order to permit of the employment of a ninety volt current, the resistance may be further reduced by short circuiting a portion thereof.

40 A voltmeter 70 is disposed intermediate mains 54 and 60 in order that the operator may check up the voltage passing through the lamp, said meter 70 in Figure 3 corresponding to meter 16 of Figure 1. Control 45 handles 17 and 18 in said Figure 1 operate line switch 53 and selector switch 62 of Figure 3.

In practice, a separate plug connection is 50 arranged upon the side of cabinet 10 for the lamp of higher voltages, such plug connection being adjacent to and of a different construction from the plug connection for said water cooled lamp.

I claim:

55 1. The combination with an ultra-violet apparatus including a plurality of lamp circuits of different voltage values, of a cooling system comprising a jacketed lamp casing, a source of electro-motive force, conduits to and from said casing for the flow of a liquid cooling medium, and a cabinet enclosing a selector switch and a pump, prime mover, radiator, and fan for circulating and cooling said medium, said prime 60 mover comprising an electric motor di-

rectly driving said pump and fan, and said selector switch being adapted to open and to close the circuit to said motor according to the voltage value of said lamp circuits.

2. The combination with an ultra-violet 70 ray apparatus of a cooling system comprising a jacketed lamp casing, a source of electro-motive force, conduits to and from said casing for the flow of a liquid cooling medium, and a cabinet enclosing a pump, prime mover, radiator, and fan for circulating and cooling said medium, said prime mover comprising an electric motor for driving said pump and fan, and in which the conduit from said casing comprises a 80 discharge pipe having an opening at its top, a vessel surrounding said pipe and having an outlet port at its bottom, and a covering for said vessel having an end for dispersing and equalizing the distribution of the 85 cooling medium as it is forced from said discharge pipe.

3. The combination with an ultra-violet ray apparatus of a cooling system comprising a jacketed lamp casing, a source of electro-motive force, conduits to and from said casing for the flow of a liquid cooling medium, and a cabinet enclosing a pump, prime mover, radiator, and fan for circulating and cooling said medium, said prime 90 mover comprising an electric motor for driving said pump and fan, and in which the conduit from said casing comprises a cylindrical vessel provided with an orificed bottom for the passage of the cooling medium into said radiator and having an upright section through which said cooling medium is vertically discharged, and a 95 transparent bell-like cap for said vessel concentrically arranged upon and depending into 100 said vessel and so disposed that its inner wall receives the impact of the jet of cooling medium from said upright section when said cooling system is normally operating.

4. The combination in an ultra-violet ray 110 apparatus of electrical circuits for different voltages, lamps for said circuits, a cooling system comprising a jacketed lamp casing in association with one of said circuits, conduits to and from said casing for the flow 115 of liquid cooling medium, a cabinet enclosing a pump, prime mover, radiator, and fan for circulating said medium, and means for opening the circuit to said motor when a different circuit is employed, and in 120 which the circuits are three in number, a single air cooled lamp being adapted to be used upon two of said circuits, the third circuit being associated with said cooling system, said circuits having a single operating 125 switch adapted to include said motor in circuit only when the last mentioned circuit is closed.
